[57] CLAIM

The ornamental design for a cantilevered chair, as shown and described.

DESCRIPTION

FIG. 1 is a perspective view of a cantilevered chair showing my new design;

FIG. 2 is a front elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is an enlarged fragmentary top perspective view of the joint of the chair of FIG. 1; and

FIG. 8 is an enlarged fragmentary bottom perspective view thereof.

The design is characterized by the specific configuration of the joint as illustrated by enlarged FIGS. 7 and 8.
